ABSTRACT

A safety device for a grain bin having four vertically disposed members being held together by a plurality of horizontally disposed X-shaped braces spaced along the length of the vertically disposed members. The bottom of the safety device sets in the middle of the floor of a grain bin and is further supported by four chains respectively connected adjacent the top of each vertically disposed member and attached at the other end thereof to a portion of the roof of the grain bin to thereby at least partially support the safety device and to prevent the safety device from tipping over. Ladder rungs are further connected at the ends thereof to two of the chains to form a ladder leading to an opening in the top of the grain bin.

Fig. 2

GRAIN BIN SAFETY DEVICE

BACKGROUND OF THE INVENTION

Persons have been suffocating in grain bins at an alarming rate by being pulled under shifting grain in the grain bins. There are two principle situations wherein this type of accident occurs. One has been in the situation wherein a person is standing on the grain in the bin while the bin is being unloaded. Since the grain moving to the bottom through the outlet opening tends to move quickly from the top layers of grain to the bottom, anyone standing on this moving grain can be completely covered with grain in a matter of seconds. The second situation has been the situation wherein the grain in the bin has become "bridged", which merely means that a pocket of air was formed in the grain, for example when frozen or crusted grain remains in place as some grain has been removed from the bin. The weight of a person stepping on or over such a pocket is usually enough to break loose the top of the "bridge" thereby causing the person to drop into the formerly air filled pocket, which then quickly fills with grain around the person because of the flow of grain started by the weight of the person.

Because of these types of situations, there has been a concerted effort to educate persons who might be around grain bins about this great danger. The accidents still continue to happen, however. Many of these accidents involve children who never received or didn't heed the warning. Because the education solution to the problem has not solved it completely, safety equipment has been developed to hopefully completely solve this grave problem. For example, U.S. Pat. No. 3,638,331 illustrates safety devices which tend to catch persons accidentally moving towards the bottom of a bin in flowing grain, and to provide something for a person to grasp to prevent the person from being suffocated. While the safety device of U.S. Pat. No. 3,638,331 is believed to be one of the best safety devices of its type heretofore devised, any improvements discovered in this regard are significant if it means that the improvement will more certainly provide a higher degree safety and provide a better means of escape in a grain bin accident of the type described above.

SUMMARY OF THE INVENTION

The present invention relates to a safety device for a grain bin. The safety device is disposed in the center of a grain bin from a point on or near the bottom of the bin, to a point at least above the level of the grain in the bin, and/or over a grain outlet opening to prevent a person standing on top of the grain in the bin from being pulled under and into the grain due to bridged grain or due to shifting of grain during a grain bin unloading process.

An object of the present invention is to provide maximum safety for a person standing or walking on top of the grain in a grain bin or other grain containing container.

Another object of the present invention is to provide a grain bin safety device which is simple and economical to manufacture and install, but which is nevertheless extremely dependable.

Other objects, advantages, and novel features of the present invention will become apparent from the following detailed description of the invention when con-

sidered in conjunction with the accompanying drawings.

BRIEF DESCRIPTION OF THE DRAWINGS

5 FIG. 1 is a perspective view of a grain bin partially cut away to show a perspective view of the safety device of the instant invention;

10 FIG. 2 is an enlarged perspective view of the present invention; and

15 FIG. 3 is an enlarged partial view of the present invention showing the manner in which the joints are formed in the present invention.

DESCRIPTION OF THE PREFERRED EMBODIMENT

15 Referring now to the drawings wherein like reference numerals designate identical or corresponding parts throughout the several views, FIG. 1 shows a safety device 10 disposed inside of a grain bin 11.

20 A plurality of upstanding vertical members 12 form four corners for the safety device 10. X-shaped cross-braces 13 are connected by nut and bolt devices 14 to the vertical members 12. The X-shaped braces are actually formed by two substantially straight tubular members which are connected centrally thereof by nut and bolt devices 15.

25 The vertical members 12 are shown as being formed of tubing with flattened ends 16 thereon, while the X-shaped braces 13 have flattened curved ends 17 thereon which mate with the ends 16 of the vertical members 12, as best shown in FIG. 3. This construction is not critical, however, and the framework of the safety device 10 may be formed in other ways and still be within the spirit and scope of this invention.

30 It is noted that the grain bin 11 has an inlet opening 18 at the top thereof and an outlet opening 19 in the bottom of the floor 20. Extending under the floor 20 is an outlet tube 21, which leads to the outside of the bin 11 through the sidewall thereof. Within tube 21 is normally disposed a power auger (not shown) for emptying the grain from the bin 11. The safety device 10 is disposed directly above the central outlet opening 19 for the reason that this is the point at which there is the greatest danger of a person inside of the bin being covered by grain. The reason for this greater danger is because most bridging of grain occurs in the center of the bin under the inlet opening 18. Also, when grain is being taken from the bin 11 through the outlet opening 19 and the tube 21, the grain in the bin tends to funnel centrally into the opening 19, thereby first taking out the grain in the general area of the safety device 10.

35 Consequently, gravity generally causes the grain on top as well as anything else on top of the grain, such as a person, to flow down into this central area. There is a very strong tendency to pull anything in the bin to the axial center of the bin directly over the outlet opening 19. Consequently, the safety device 10 is very likely to catch a person involuntarily traversing this path and holding such person above the bulk of the grain. Additionally the vertical and X-shaped horizontal braces provide a person involved in such an accident very good access for grasping the safety device 10 and providing a means of escape from the flowing grain. The fact that the horizontal braces cross at the respective

50 centers thereof and extend directly over the center of the outlet opening or center of the bin, is a definite improvement over the brace structure 41 of U.S. Pat. No. 60 65

3,638,331. This is true because theoretically a person could be pulled down through the center of the square shown in FIG. 6 of that patent without being stopped by the horizontal braces. Additionally, the side access for grasping is better when using X-shaped braces 13 as in the instant invention. In short, while the safety device including braces 41 of U.S. Pat. No. 3,638,331 is very good and safe, the safety device 10 of the present invention is better and safer.

Preferably the safety device 10 is supported from the roof 22 of the grain bin 11 by lines or chains 23, in addition to being supported at the bottom thereof on the floor 20. This construction prevents the safety device 10 from tipping over. This connection of chains 23 to the roof 22 may be effected as shown in FIG. 9 of U.S. Pat. No. 3,638,331. The connection of chains 23 to the safety device 10 is shown in FIG. 3 by loop devices 24, having a threaded nut 25 on the underside thereof, noting that the manner of making these connections are not critical except to the extent of being certain that they are securely fastened.

A plurality of ladder rungs 26 are connected to two of the supporting chains 23 for facilitating an easy escape to route to the top opening 18 for a person inside of the bin 11. More rungs 26 may be connected to 25 other of the chains 23 if desired.

It can therefore be seen that a lifesaving safety device has been disclosed which accomplishes all of the objects set forth above. Obviously many modifications and variations of the present invention are possible in light of the above teachings. It is therefore to be understood that, within the scope of the appended claims, the invention may be practiced otherwise than as specifically described.

I claim:

1. A safety device for a grain bin comprising: four vertical members having top and bottom ends; a first horizontally disposed substantially X-shaped brace having the ends thereof rigidly affixed to respective ones of said vertical members near the top thereof; a second horizontally disposed substantially X-shaped brace having the ends thereof rigidly affixed to respective ones of said vertical members near the bottom thereof; a third horizontally disposed substantially X-shaped brace having the ends thereof rigidly affixed to respective ones of said vertical members intermediate the top and bottom thereof; each respective one of said first, second and third X-shaped braces lying substantially in one plane; a continuous vertical completely open space being formed between adjacent vertical members from the top to the bottom thereof to allow unimpeded access to the X-shaped members; and

means for affixing said safety device within a grain bin.

2. A safety device for a grain bin as defined in claim 1 wherein said affixing means includes means for attaching said safety device to a grain bin roof.

3. A safety device for a grain bin as defined in claim 2 wherein said means for attaching the safety device to a grain bin roof includes a means for suspending the safety device to the roof.

4. A safety device for a grain bin as defined in claim 3 wherein said suspending means includes four chains, each chain being attached at one end to the bin roof and the other end thereof at a point on the safety device adjacent the ends of the top-most horizontal X-shaped brace.

5. A safety device for a grain bin as defined in claim 4 wherein a plurality of horizontally disposed rungs are attached to two of said chains to form a ladder means leading to a bin opening.

6. A safety device for a grain bin as defined in claim 1 wherein the horizontal X-shaped brace is disposed adjacent the top of said vertical members and at least one additional horizontally disposed substantially X-shaped brace is connected at the ends thereof to respective ones of said vertical members at a point intermediate the top and bottom of the vertical members.

7. A safety device as defined in claim 6 wherein a substantially X-shaped brace is connected to said vertical members at the bottom thereof.

8. A safety device for a grain bin as defined in claim 1 wherein the longitudinal center of the safety device corresponds to the axial center of the grain bin.

9. A safety device as defined in claim 1 wherein the longitudinal center of said safety device is directly above an outlet opening in the grain bin.

10. A safety device for a grain bin comprising: four vertical members; at least one horizontally disposed substantially X-shaped brace having the ends thereof rigidly affixed to respective ones of said vertical members; and means for affixing said safety device within a grain bin, said affixing means including means for attaching said safety device to a grain bin roof, said means for attaching the safety device to a grain bin roof includes a means for suspending the safety device to the roof, said suspending means includes four chains, each chain being attached at one end to the bin roof and the other end thereof at a point on the safety device adjacent the ends of the top-most horizontal X-shaped brace, and wherein a plurality of horizontally disposed rungs are attached to two of said chains to form a ladder means leading to a bin opening.
